CONTAINER MADE OF PAPER

Marshall E. Gazette, Boston, Mass., assignor to
Boothby Fibre Can Company, Boston, Mass., a
corporation of Massachusetts

Application December 9, 1933, Serial No. 701,633

4 Claims. (Cl. 229—5.5)

This invention relates to improvements in containers made of paper. More especially it relates to containers of the cylindrical "paper can" type, and particularly to improving the wall structure 5 thereof, and the cover-cap closures for fitting removably over the mouth of a can body.

Cylindrical containers of the general class to which the invention relates are ordinarily made of a tube of paper board permanently closed and 10 sealed at one end in any suitable way, as by a crimped-in closure disk. Covers are made likewise, a short tube constituting a flange of the cover, enclosing the top of the can body. Such cans are often desired to serve as accurate measures of contents, as when used for holding liquids, 15 as beverages, or semi-liquids, powders, etc. This is easily possible if the measure be effected by a filling flush with its top edge. Therefore, it is particularly desirable that the cap closure be applicable easily, and without danger of spilling any of the contents; yet when applied the cap must be tight against seepage of liquid; and it should be able to prevent leakage even when not 20 fully seated, as when contents are somewhat heaped. Also it is important that air or other gas, which may be entrapped when the cover is applied, or be generated by contents, shall be 25 permitted to escape harmlessly.

Present styles of cylindrical paper cans having 30 a tightly fitting cover offer difficulty at times to a person applying the cap closure, owing to the raw edge of cut paper at the lip of the can body, and the similar raw cut edge on the flange of the cover. The nicety of fit makes it difficult to apply the closure without upsetting the raw cut 35 edge; and the one edge obstructs the other.

The invention eliminates the bringing together of two close fitting raw cut edges, making one of the edges smoothly rounded by a doubling inward 40 of the tubular stock. On a can of ordinary construction, cylindrical from bottom to top, with the doubling applied to the cover, this proves to be not appreciably more prominent than where a single-thick cover flange hugs tightly a single-thick rim portion of can.

It also provides a one-way passage in the cover 45 for vent and harmless escape of gas under pressure, which may become entrapped or which may accumulate within a capped container.

And it provides a cover-flange wall whose inner fold and interior surface have been reorganized and exercise a cushion-grip, assuring a liquid-tight engagement of the flange around the can body top.

It is an important feature that well-known operating methods, and machinery now available, can do what is requisite. A further step for completing the cover comprises merely the slitting 55 of the exterior wall of the flange at one or more strategic locations. The short length of tubular

stock taken for the making of the cover flange has to be longer than has been customary for a single-thick cover flange. The can body may be of an usual construction and its cylindrical walls may be single-thick from bottom to top; but with a cover as described the top raw edge of the body becomes unobjectionable.

However, if the body-wall be in-turned the customary single-thick raw edged construction of cover flange becomes unobjectionable. In this 10 case the body wall acquires certain special advantages. The doubled wall may house, covered within its two folds, a layer of special purpose material which it is desired not to expose. This material might be some form of heat insulation, 15 or a special paper such as southern kraft which has strength but is not sightly; or the doubling may eliminate need for a finish layer on the wall stock. In this construction the body wall is 20 smooth and of finished aspect without there being any exposed raw edges. The extra stock and strength attained may give such qualities of permanence that the limitation of the paper can to single service usage may be considered removed, and the paper can cup or other utensil 25 may thus enter the class of dishes suitable for repeated use.

According to the invention a length of the tubular stock is turned inward forming a double-thick cylindrical flange or wall with a rounded 30 fold at its edge. I have discovered that in the case, for example, of such a cover applied to a raw-edged single-thick body wall, there is thus attained an ease of application like that of a loose cover, yet the cover proves to be equal or 35 superior to covers that are tight, as regards security of position, closeness of fit, and non-leakage.

The cover may consist of a closure disk to 40 which is crimped or otherwise secured the in-turned short tube which constitutes the flange. Preferably, the in-turned raw cut edge of the tubular stock of this flange will be tucked loosely 45 into the crevice at the crimp, at the disk end of this short tube. Gases can then pass around this 50 end and into the annular crack in the midst of the double-thick flange wall, to where a slit or slits through the outer thickness of the double flange wall permits escape of these gases, if under pressure, although air at atmospheric pressure 55 has little or no ability to enter.

It is one feature that the smooth and tight organization of fibres in the paper stock of the in-turned flange wall becomes somewhat loosened by the sharpness of its in-turning, so that its 55 fibrous structure thus acquires cushioning characteristics whereby the flange engages the can rim with adequate closeness notwithstanding that the mouth of the cap flange may be of size to engage easily over the can rim. The ease arises 60

from the fact that the stock yields slightly, but it does in fact appear to have a close fit, which gets progressively tighter as the cap is pressed to its seat.

5 It is intended that the patent shall cover, by suitable expression in the appended claims, whatever features of patentable novelty exist in the invention disclosed.

In the accompanying drawing:

10 Figure 1 is an elevation of a cylindrical paper can body, and of a flanged cover-cap closure therefor, both embodying features of the invention, portions being broken away to medial section;

15 Figure 2 is an elevation showing a cover like that of Figure 1 seated on a can whose wall is only single thick, with portions broken away for clearness; and

20 Figure 3 is an elevation of a modified cap structure, in medial section, showing a cap disk which may be lifted out of its flange.

Referring to the drawing, the can body 10 may be the usual single-thick cylindrical tube of helically wound paper, as in Figure 2, in whose bottom end a permanent closure disk (not shown) 25 may be crimped or otherwise secured for serving as the bottom of the container. Such a helically wound tube comprises a plurality of plies of the paper stock, but this composite structure 30 acting as a unit, however it may be internally composite, is herein referred to, for convenience, as "single-sheet-thick" stock, by contrast with instances such as in the cover flange, or in the body in Figure 1, where one such composite 35 thickness is laid over upon another composite thickness, and the two are described herein as "double-thick". And, in the present case, where the stock is folded upon itself, thicknesses may be referred to as the inner limb and the outer 40 limb of the double-thick stock, the inner limb being nearer the axis of the container body.

The cover may be a short length of helically wound paper tube having a closure disk 12 secured in one end, herein shown crimped to the 45 tube, the annular crimp 14 making an ordinary liquid-tight joint. However, the initial tubular stock taken for this is longer than the desired length of flange, the extra length being turned inward and laid within and against the outer 50 portion of the tube, to provide a double-thick cover flange whose inner layer or thickness is indicated at 16 and whose outer is represented at 18.

The in-turning of portion 16 may be accomplished by the usual die mechanism as heretofore used for turning in the end of a tube, or for crimping annular seals. The extreme end of the tube first is turned inward, making an annular fold in the paper stock; and then, as the 60 in-turned end moves further inward, this fold traverses the stock, and ultimately will have traversed the entire in-turned portion of the stock. In so doing the sharp folding disturbs and loosens the fibrous structure so that the portion 16 becomes in the nature of an annular cushioning interior face wall for the cap flange. Also the in-turning puts the stock that is in the portion 16 into a cylindrical form of smaller diameter than that which is initially occupied, 65 and this adds to the effect of the folding, in producing a multiplicity of slight wrinkles or creases 26 in the in-turned stock. These can be seen extending in circumferential direction interiorly of the flange. They make a succession 70 of ridges, projecting inward toward the axis

7 to a very slight extent; and as the inmost surface of the in-turned layer has a circumference substantially less than that of the exterior of the double-thick flange, which was originally its own diameter, there doubtless is a thickening 10 of this layer of fibrously loosened paper stock. The whole effect is that of a cushioned surface at the interior of the flange. The fold 22 itself constitutes a smooth, rounded enlargement of diameter of the inner layer.

The nicely rounded and finished flange edge 22 is important in that it facilitates the entrance of a raw cut edge of the can lip into the cap when a cap is being applied to a can. When the sizes are made to fit properly, the cushion 16 provides a desirable slight yielding of interior surface of flange, which affords an easy reception of the can rim, yet there is no apparent looseness which might be objectionable as giving an initial impression that the cap would not constitute a 15 sufficiently tight closure. The cap may be easily rotated on the can when the can rim is only slightly within the flange. But, as the cap is pressed further home, more and more of the cushion 16 grips the can rim, with the creases 20 contributing to the gripping action until, when the cap is say two-thirds of the way to its seat, the can rim will be gripped so tightly that it cannot easily be rotated by hand. And when the cap is fully seated the grip becomes still stronger. 25 Liquid cannot escape between the flange and the can rim.

It is important in containers of this sort that the cap shall be tight even though a heaping of contents shall prevent the cap from being fully 30 seated. The cap closure of the invention effectively provides for such a contingency.

Heretofore it has been an unsolved problem to provide for a harmless escape of gases which may be entrapped within the container, as air when the cap is being put on, or which may be released or generated by contents. A considerable body of air, between the disk and the edges of the flange, is bound to be trapped under the cap as it is applied. With prior constructions this air has had 40 to escape around the flange. In order for it so to escape, a person has had to take pains to seat the cap gently. If forced on suddenly there has been the danger that contents, especially liquid, might be forced out through the bottom annular 45 seal, or the bottom itself be driven out.

The present invention provides for venting these interior gases harmlessly through the cap flange wall, without risk of loss of liquid through the vent. To this end the in-turned portion 16 of the flange has its inner edge tucked loosely into the interior annular crevice or groove 24 at the disk crimp 14. Preferably the tucked-in edge will have been preliminarily compressed or beveled as at 26 to facilitate passage of gas around it and into the annular cylindrical crack 28 between the inner and outer thicknesses of flange walls. From this crack 28 the gases may escape to atmosphere through one or more slits 30 in the outer thickness of the flange. The fluidity of gases permits them to take the easiest course out; and the path to crack 28 and thence through a slit 30 is that easiest course, yet this path is sufficiently restricted by the pressure of the inner upon the outer thickness, so that gas will pass out only when under a little pressure, and atmospheric air finds difficulty in entering. The vent is always available in case gases may be generated by container contents.

In certain uses of cap closures of this general 75

type, it may be desirable to have the cap disk removable from its flange for getting access to contents of the capped container. One example of such a use is where the paper container, of 5 large size, is employed in place of the present tin cans for holding ice cream for retail distribution. In such a case the ice cream comes to the retailer in the paper container. The cap flange, however, has become frozen on the top of the container, and 10 may not be easily removed.

The present invention lends itself admirably to this situation. The in-turned thickness of flange wall presents an annular edge interiorly which may constitute a seat for a closure disk 12', as 15 seen at Figure 3. The crimp 14' in this case may be a mere inward roll of the tubular stock, holding the disk to its said seat. Such a cap may not be liquid tight, but is suitable for the mentioned containers for ice cream. And the disk 12' easily 20 may be disengaged from its flange and be lifted out from its flange with a suitable sharp tool. And the cap flange continues on the rim of the container, and may be forced down over the rim until the in-turned portion of the flange is seated on 25 the edge of the rim of the container body, reenforcing that rim.

It is also a feature of the invention that a desired aspect of general cylindricality is preserved for a capped can, which is made to have more 30 "finish" and distinctiveness than some cans of the general sort heretofore available.

The improvement in the container body by making its wall double thick, Figure 1, turns the raw edge down into the crevice at the bottom of 35 the container body 10', as described for the cover cap. The body wall thus has the same surface material outside and inside, and, in effect, has no raw edge whatever. The rumpled aspect of surface illustrated and described with reference to 40 the flange of the cover can be removed from the body interior by suitably smoothing the material. Containers used for food, in addition to being pure, strong and sound, must also have outside and inside finish of inviting aspect. By this 45 construction one side of the paper stock from which the wall is made need not have a finished surface. This freedom gives opportunity for using stock which has, on its face that is to be doubled into the middle, out of sight, some useful 50 material which may be less slightly than would meet the standard of finish required on an exposed interior surface. It may, for example, be a heat-insulating material, to make a cup comfortable for holding a hot drink in the hand; or 55 a strengthening material, or a structurally suitable but less expensive body material. Southern kraft paper, strong, useful and cheap, but not pleasing to the sight, is an illustration. If it be desired to use for insulation a bright metal foil, 60 as aluminum foil, the low coefficient of heat loss by radiation may best be made available by in-turning with a die that leaves the in-turned thickness at a slight distance from the outer thickness, even though the gap between thicknesses be 65 only microscopic. The cover for such a body may have either the double thick flange herein illustrated, or any ordinary single thick flange with raw edge of the type hitherto in ordinary use.

The constructing of the body wall double thick, 70 with finished rounded top edge and without any exposed raw edge, provides elements of strength and permanence which may permit the designing of containers for repeated use, instead of for

single service and wastage, as paper containers have hitherto been designed.

I claim as my invention:

1. A closure cap of paper for a container, comprising a disk with annular, double-sheet-thick 5 cylindrical flange whose inner limb is an integral continuation of the outer limb, turned inward and laid against said outer limb; there being a thin passage, around the end of said inturned limb of flange, to the annular crack between the two 10 limbs of flange, and a vent through the outer limb of the flange, whereby gases under pressure within a capped container may escape to atmosphere.

2. A closure cap of paper for a container, comprising a disk with annular, double-sheet-thick cylindrical flange whose inner limb is an integral continuation of the outer limb, turned inward and laid against said outer limb; said disk and flange being secured together by an annular 15 crimp, and said crimp providing an annular crevice interiorly of the cap, into which the end of said inturned limb of the flange is tucked loosely; and a vent through said outer limb of the flange; there being a restricted passage around 20 the said tucked-in flange portion, to the crack between the two limbs of flange, whereby gas under 25 pressure within a capped container may escape to said vent.

3. A combination of container body, closure 30 disk therefor, and flange; wherein the flange combines with both disk and body to make a closure for the container when the cap is on, and is readily separable from the disk to remain combined with the body as a reinforcement which 35 may be seated on the edge of the rim of the body when the body is open; the said flange being of plural-ply helically-wound paper stock in-folded at one end to double-thickness and there provided with an in-face for fitting the container; 40 and being in-turned at its other end for engaging axially outside of the disk, this engagement being one at which the disk is by upward pull easily separable from the in-turned flange; and the said in-face and the out-face of the container 45 both being free from interfering projections, so that the one is free to slip over the other from the position of normal closure; whereby when the disk is removed from the flange, the cap being on the body, the flange can be slipped down 50 over the container until the in-turned portion of the flange is seated on the edge of the container-body.

4. A combination of cylindrical container body, closure disk therefor, and cylindrical flange; 55 wherein the flange combines with both disk and body to make a cap closure for the container when the cap is on; means at said flange for venting air trapped within the cap closure; the said flange having an inner face for fitting the container, and being in-turned for engaging outside of the disk, in direction parallel to the axis; the said disk at its margin having an annular groove in its upper face, in which groove the said in-turned portion of flange engages; the marginal 60 face of the disk under said groove constituting a prominent annular bead, interiorly of the cap at the juncture of disk and flange, for resting on the top edge of the container, thereby to space the plane central part of said disk a distance 65 above the top of the container when said cap is fully seated thereon.

MARSHALL E. GAZETTE.
